HAND LOTION DISPENSING JAR

Arthur Morris, Beverly Hills, Calif.

Application May 14, 1948, Serial No. 146,360

Term of patent 3½ years

(Cl. D86—10)

To all whom it may concern:

Be it known that I, Arthur Morris, a citizen of the United States of America, residing at Beverly Hills, in the county of Los Angeles and State of California, have invented a new, original, and ornamental Design for a Hand Lotion Dispensing Jar, of which the following is a specification, reference being had to the accompanying drawing, forming part thereof, wherein

Fig. 1 is a top plan view of a hand lotion dispensing jar embodying my new design; and

Fig. 2 is a side elevational view of the same.

I claim:

The ornamental design for a hand lotion dispensing jar, substantially as shown.

ARTHUR MORRIS.
